United States Patent Office.

ELLERY P. RALPH AND JAMES HANNAN, OF GALLIPOLIS, OHIO.

Letters Patent No. 93,746, dated August 17, 1869.

IMPROVEMENT IN TINSMITHS' SHEARS.

The Schedule referred to in these Letters Patent and making part of the same.

To all whom it may concern:

Be it known that we, ELLERY P. RALPH and JAMES HANNAN, of Gallipolis, in the county of Gallia, and in the State of Ohio, have invented a Notch-Cutter for Tinsmiths' Shears, to be attached to bench-shears; and we do hereby declare that the following is a full, clear, and exact description thereof, reference being had to the accompanying drawings, and to the letters of reference marked thereon, in which—

Figure 1 is a perspective view of the invention, and

Figure 2 is a sectional view, showing, in perspective, the movable die or cutter attached to the movable handle of the shears.

The nature of our invention consists in cutting dies with adjustable guides attached to the stationary die, and fastening said dies to tanners' bench-shears for the purpose of notching tin, as will be hereinafter more fully set forth.

To enable others skilled in the art to make and use our invention, we will proceed to describe its construction and operation.

In the construction of our invention, in fig. 1,

A represents the work-bench, into which is set the shears B, in the ordinary manner, and to which is attached our invention.

a is the lower die, which is fastened to the lower or stationary arm or handle of the shears, by screws 1, 2, and 3.

b, the rear movable gauge, for regulating width of the notch cut from the side of the tin or metal. It has a slot cut in it, through which screw 1 passes, and on which, when required, it slides. Then the screw is tightly-drawn and remains so until it becomes necessary to change the width of the notch.

c, the front gauge, constructed with a slot, also, to allow it to be moved up and down, as required, to determine the length of the notch cut out of the material. With the present die, a notch can be cut out fully an inch in size.

d is simply a corresponding cutting-die made to correspond in shape with the stationary die, and is securely attached, by screws, to the moving-arm of the shears. This die is seen in fig. 2.

In the operation of our invention, it is intended to supply a much-felt want in the trade to which it appertains.

It is well known that in making ware with a rim on

the top edge strengthened by inverting wire therein, it is necessary to notch the upper ends of the edges that are soldered together, to prevent the sides from being double where the edge is turned over the wire. The sides have to be notched, and to do this, ordinarily, there is a great deal of labor and time wasted, as the trade has no gauge by which to do, and in order to make all the notches alike and a good fit, compasses must be used to space the notch to be cut out; but, with our invention, we attach it to the common bench-shears, and set the gauges b and c to suit the required size we wish to cut out; and with our invention set as required, the different pieces are cut all of a uniform size for all vessels of any given quantity, and the dies and gauges will remain at that fixed size of notch until it is necessary to change the size of the notch to be cut, which can be immediately done by changing the gauges b and c, by loosening the screws and sliding the gauges, as required, either to enlarge or lessen the size of the notch.

Figure 3 represents the notches cut out on the sides which are to be soldered together, and

Figure 4 represents the same pieces soldered together, and after all the parts of the vessel are prepared, the upper edge is turned over on the wire, or the wire is inserted as is common in the trade, when the vessel can be completed.

By means of our invention, we can make a much more correct finish, and save labor and time in doing so.

Having thus described the construction and operation of our invention,

What we claim as new, and desire to secure by Letters Patent, is—

In combination with the shear B, the stationary die a, having adjustable gauges b and c, and movable die d, constructed to operate substantially as and for the purposes set forth.

In testimony that we claim the above-described improvement, we have hereunto signed our names, this day of May, 1869.

ELLERY P. RALPH.
JAMES HANNAN.
